UNITED STATES PATENT OFFICE

JOSEPH P. RUTH, JR., OF DENVER, COLORADO

FLOTATION METHOD

Application filed January 28, 1931. Serial No. 511,448.

This invention relates to improvements in methods for operating flotation machines of the type employed in separating mineral values from gangue.

5 In the mining of metals it is now common practice to employ flotation machines for the selective separation of the minerals from the gangue. It has been found from extensive experiments that flotation machines operate 10 at their highest efficiency only when they operate at maximum capacity and with the present forms of flotation machines this is a condition that prevails only in mines where 15 the ore supply is equal to or greater than the capacity of the machines employed.

A flotation machine is composed of a plurality of units or cells, each having a receiving conduit and a frothing chamber, an impeller is located in a passageway that connects the receiving conduit and the frothing chamber and this transfers the pulp from the former to the latter and mixes it with air. The froth overflows into a froth launder and the tailings from each cell, except the last, is 25 delivered to the receiving conduit of the next cell in the series and the tailings from the last cell is conducted to a tailings dump. The pulp is fed into the receiving conduit of the first cell or unit in the series and therefore 30 passes successively through the several cells of which the machine is composed. Since some of the values are removed in each cell, it is evident that the richness of the pulp decreases as the pulp progresses through the 35 machine.

In designing flotation machines for mines, it is customary to provide for sufficient capacity to take care of the maximum output of the mine and as a result the machines 40 frequently operate on a supply that is considerably below the capacity for which the machine was designed and therefore the efficiency at which the machine operates is below maximum which means that there is a loss of mineral values that could have been 45 saved if the supply of pulp supplied were larger.

I have found that if a portion of the tailings, instead of being transferred to the dump, is returned to the receiving conduit

of the first cell of the machine, it is possible to operate the machine at maximum capacity at all times, regardless of the fact that the supply of pulp is less than the capacity of the machine. It is obvious that if the machine was operating at full capacity in the ordinary way and the supply of pulp cut off and all of the tailings returned to the intake conduit of the first cell the quantity of pulp circulating through the machine would remain the same except for the loss due to the froth overflow. If fresh pulp to the extent of one-half of the capacity is supplied to the intake conduit of the first cell and one-half of the tailings returned, the machine will be 60 operating at maximum capacity and consequently at maximum efficiency.

In order to more clearly define the method described above an apparatus by which it can be carried out will now be described and for 70 this purpose reference will be had to the accompanying drawing in which:

Fig. 1 is a top plan view of an assembly of cells showing the launder by means of which a portion of the tailings are returned to the receiving conduit of the first cell;

Fig. 2 is a side elevation of the cell assembly; and

Fig. 3 is a transverse section through one of the cells.

The assembly illustrated comprises six cells 4 arranged one above the other as shown in Fig. 2, each of the cells has a receiving conduit 5 and a frothing chamber 6. Line 7 in Fig. 3 indicates the pulp level and the pulp overflow is indicated by reference number 8 while the froth overflow is designated by numeral 9. A spout 10 is located underneath each pulp overflow and is inclined so as to carry the pulp to the receiving conduit of the next higher cell. A froth launder 11 extends underneath all of the froth overflows. The spout 10 from the last cell in the series is connected with a launder 13 that extends to the receiving conduit of the lowermost cell in the series. In order to vary the proportion of the total of the tailings that are returned, a plate 14 is secured to the inside of the spout 10 by a hinge, the hinge is located at the lower edge of the plate 14 and its 100

position is controlled by a screw 15. If plate 14 is moved so as to contact with both sides of spout 10, all of the tailings will be returned, if it is moved up against the side to which it is hinged, none of the tailings will be returned and any proportions between these extremes can be returned by moving plate 14 to the corresponding intermediate position.

10 The cells are each provided with an impeller 16 that is secured to the lower end of the impeller shaft 17.

15 The apparatus described is merely illustrative and applicant does not want the same to be considered as in any way limiting the scope of his claims.

20 From the above it is evident that by returning a sufficient amount of tailings and mixing them with the original pulp, the machine can always be operated at maximum capacity and efficiency. It is also evident that by returning a portion of the tailings and having them pass through the machine, they will be subjected to a second operation that 25 will remove any mineral values that would otherwise have been lost.

30 I consider that the discovery that flotation machines operate at greatest efficiency when operating at full load capacity and that this condition can always be obtained regardless of the actual amount of pulp available by the simple expedient of returning a portion of the tailings to the intake conduit of the first cell constitutes my invention and it is of great 35 practical importance in this art.

Having described the invention what is claimed as new is:

40 1. The method of operating a series connected group of flotation machines so as to obtain the maximum efficiency when the pulp available is less than that required for the capacity corresponding to maximum efficiency which consists in returning tailings from the last cell of the series to the intake conduit 45 of the first cell in such amount that the returned tailings and the original pulp supply will equal the amount necessary for maximum efficiency.

50 2. The method of operating a flotation machine, having an intake conduit and a tailings discharge, at maximum efficiency when the pulp available is less than that which is required for maximum efficiency which consists in returning so much of the tailings to 55 the intake conduit that the returned tailings and the supply of untreated pulp together produce a load that corresponds to that which is required for maximum efficiency.

60 In testimony whereof I affix my signature.
JOSEPH P. RUTH, JR.

DISCLAIMER

1,886,979.—*Joseph P. Ruth, Jr.*, Denver, Colo. FLOTATION METHOD. Patent dated November 8, 1932. Disclaimer filed August 23, 1935, by the patentee.

Hereby enters this disclaimer to limit the scope of claims 1 and 2 of said Letters Patent to the method therein defined only when made effective through certain specifically characterized apparatus of that type illustrated in said Letters Patent, to wit:

Flotation machines wherein the tailings discharge from each cell unit is a substantial distance above the pulp feed inlet to said cell unit and separate from and below the froth discharge from said cell unit, and wherein the impeller element has an operative capacity sufficient to maintain the feed compartment of its cell unit substantially empty.
